UNITED STATES PATENT OFFICE

SVEN LARSSON, OF SANVIKEN, SWEDEN

DISCHARGING ARRANGEMENT IN SHARPENING MACHINES FOR RAZOR BLADES

Application filed April 13, 1928, Serial No. 269,830, and in Sweden April 29, 1927.

This invention relates to a discharging arrangement in sharpening machines in which the belt is arranged to move the blades in horizontal position to a discharging position on the under part of the belt and in which in the path of the blades a movable member is arranged in such a way, that its movement under the influence of the fed blades causes the blades in horizontal position to be released from the belt in vertical direction.

One embodiment taken as example of the invention is shown in the accompanying drawings. Herein is Fig. 1 a side view of the discharging arrangement. Fig. 2 shows the discharging arrangement seen from the side, with the parts in another position than in Fig. 1. Fig. 3 is a section along the line III-III in Fig. 1.

According to Figs. 1-3 the endless belt or chain is indicated by 1. This is fed in the direction of the arrow *a* with the aid of two guiding or chain wheels, not illustrated. The belt or chain is provided with projections or catching members such as pins 2.

At the discharging position, which according to Fig. 1 is arranged at the under part of the conveyor in order to use the gravity of the blade in discharging, guides 3 are arranged, which are provided with cams 4, against which the blade hits during the feeding, and by which it is brought a little away from the conveyor, but not more than the catching members 2 continue to pull the blade forward. Means arranged for holding the blades during the transport from the feeding arrangement to the discharging arrangement, but said means are not shown, as they fall outside the scope of the invention. On the shaft 5 is journalled a lever 6, which is provided with a bevelled surface 7, which normally rests in a depression 15 in the guides 3, Fig. 2. The lever 6 is by means of a link 8 connected to a lever 9, which is turnably journalled on a pivot 10 and is provided with two arms 11 and 12. The arm

11 is provided with a thrust surface 13 intended in the position shown in Fig. 2 to thrust the blade out from the conveyor. The arm 12 is intended to act as a bearing surface or support for the blade in the position shown in Fig. 1. The lever is acted upon by a spring 14, which normally holds it in the position shown in Fig. 2. Pins 16 are arranged under the conveyor at a distance from each other which corresponds to the distance between the holes in the blades 17.

The arrangement works in the following manner:

At the moving forward of the belt 1 through the guides 3, the blade is lifted from the belt by means of cams 4, only no higher than that the catching members 2 on the belt still move the blade forward. At the forward movement of the blade its forward end strikes in a certain position against the bevelled surface 7 on the lever 6, which is hereby turned from the belt whereby the same by means of the link 8 lifts the arm 12 up against the belt and prevents the blade 17, from falling down or leaving the catching members on the belt. When the blade has passed the lever 6, this latter is moved back into its initial position by the spring 14. Hereby the arm 12 is also moved back, whereby the blade 17, is released. At the same time the arm 11 is pulled down against the blade 17, and strikes it by means of the thrust surface 13 from the belt. The blade is caught by the pins 16 and stacked.

Having now described my invention, what I claim as new and desire to secure by Letters Patent is:

1. A discharging mechanism comprising a conveyor for transporting an article with a hole, a pin upon which the article is adapted to be caught, a support which is movable in respect to the pin and upon which the article is adapted to be rested, and movable means connected with the support being actuated by the article in passing toward the

pin to move the support first into a receiving position then into a release position.

2. A discharging mechanism comprising a conveyor for transporting an article with a hole, a pin upon which the article is adapted to be caught, a support which is movable in respect to the pin and upon which the article is adapted to be rested, movable means connected with the support being actuated by the article in passing toward the pin to move the support first into a receiving position then into a release position, and a thrust member acting in conjunction with said support to displace the article from the conveyor for reception by the pin.

3. A discharging mechanism comprising a movable conveyor having a catching member for engaging the hole of a blade, a pin by which a blade is adapted to be impaled, means by which the blade is slightly separated from the conveyor during passage toward the pin, and a thrust member movable toward the blade upon arrival at the pin to dislodge the blade from the catching member and impale it on the pin.

4. A discharging mechanism comprising a movable conveyor having a catching member for engaging the hole of a blade, a pin by which the blade is adapted to be impaled, a cam in the path of the blade and directed to one side of the conveyor to slightly separate the blade from the conveyor during passage toward the pin, and a thrust member movable toward the blade upon arrival at the pin to dislodge the blade from the catching member and impale it on the pin.

5. A discharging mechanism comprising a movable conveyor having a catching member to engage the hole of a blade, a pin by which the blade is adapted to be impaled, means in advance of the pin to slightly separate the blade from the conveyor during passage toward the pin, and a pair of arms movable to alternately support the loosened blade initially preventing its falling from the catching member and to thrust the blade from the catching member for impalement by the pin.

6. A discharging mechanism comprising a movable conveyor having a catching member for engaging the hole of a blade, a pin to impale the blade, a feeler pivoted in advance of the pin and which is depressed by the blade during its passage toward the pin, a pivoted lever having support and thrust arms, a connection between the lever and feeler rocking the lever in one direction to move the support arm and receive the blade upon said depression of the feeler, and resilient means connected with and rocking the lever in the other direction upon release of the feeler by the blade and registration of the hole with the pin to move the thrust arm against the blade for impalement by the pin.

7. A discharging mechanism comprising a conveyor having a catching member on the

under side for engaging a hole in the razor blade, a movable thrust member for pushing the blade off of the catching member and away from the conveyor, and a feeler movably mounted below the conveyor for movement of the thrust member toward the blade during passage of the blade over the feeler toward the thrust member.

In witness whereof, I have hereunto signed my name.

SVEN LARSSON.
